[57] CLAIM

The ornamental design for a lift for raising and lowering an object, as shown and described.

DESCRIPTION

FIG. 1 is a perspective view of a lift for raising and lowering an object of my new design;

FIG. 2 is an enlarged side elevational view of the right side of FIG. 1;

FIG. 3 is an enlarged elevational view of the left side of FIG. 1;

FIG. 4 is an enlarged rear elevational view of FIG. 1;

FIG. 5 is an enlarged top view of FIG. 1; and

FIG. 6 is an enlarged bottom view of FIG. 1.
